UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE-EXCHANGE SYSTEM.

Application filed September 8, 1920. Serial No. 408,852.

To all whom it may concern:

Be it known that I, ALBEN E. LUNDELL, a citizen of the United States, residing at New York, in the county of New York, State 5 of New York, have invented certain new and useful Improvements in Telephone-Exchange Systems, of which the following is a full, clear, concise, and exact description.

This invention relates to telephone exchange systems and more particularly to systems in which a link circuit with which a repeating coil is associated is used for extending connections to points at varying distances.

15 In systems of the above mentioned type, it is desirable that devices be provided by means of which the ratio of the number of turns of the secondary winding to the number of turns of the primary winding of the 20 repeating coil may be made variable. This is necessary in order that proper transmission may be accomplished irrespective of the impedance characteristics of "loading", of the line to which connection has been 25 established.

In certain systems in which means have been provided for varying the ratio of the repeating coil windings, the result has been accomplished under the control of the sender 30 as a result of a selective operation of an automatic switch. This type of operation places an additional burden on the sender since it tends to complicate the sender circuits. In addition, an extra time interval is 35 required in which to accomplish the necessary selective operation.

In systems such as that shown in my co-pending application Serial No. 408,851, filed September 8, 1920, the selection of a desired repeating coil ratio is accomplished in 40 accordance with distinctive electrical characteristics of the outgoing lines to which the link circuit has access.

It is the object of this invention to provide an improved means for varying the 45 ratio of the windings of a repeating coil in accordance with distinctive electrical characteristics of the trunks to which it has access.

50 It is a further object of this invention to provide means which shall be simple and efficient and by means of which a wide range of variation of the repeating coil winding ratio may be obtained.

55 A feature of the invention is the use of

a switching device associated with the link circuit and controlled by means of impulses supplied over the terminals of an outgoing line with which the link circuit has been associated. The number of impulses supplied to the switching device will vary in accordance with the particular outgoing line which has been selected. Different numbers of impulses will be supplied to the terminals of outgoing lines to characterize these lines with respect to their transmission qualities. 60

It is thought that the invention will best be understood from the following detailed description, reference being had to the accompanying drawing. 70

In the drawing, the figure shows so much of a telephone system as is necessary to an understanding of the invention.

The invention has been shown applied to a semi-automatic system employing power 75 driven switches, but since it is obviously capable of adaptation to many types of telephone systems it is not to be limited to the system as disclosed.

The operation of the system is as follows: 80

When the subscriber at the substation 1 removes his receiver from the switch hook, a circuit is completed from grounded battery, left hand winding of line relay 2, outer armature and back contact of cut-off 85 relay 3, through the closed loop of the calling subscriber's line, inner armature and back contact of relay 3, right hand winding of line relay 2 to ground. Relay 2 is energized and completes a circuit from grounded battery, lamp 4, right hand armature and front contact of relay 2 to ground. The resultant illumination of lamp 4 informs the operator that the associated line is calling. She thereupon inserts answering plug 5 into jack 6 whereupon a circuit is completed from grounded battery, winding of relay 7, sleeve contacts of plug 5 and jack 6, winding of cut-off relay 3 to ground. Relays 7 and 3 are energized in this circuit. 90 Relay 3, upon energizing, opens the circuit of line relay 2 and this relay de-energizes, causing lamp 4 to be extinguished. 95

The operator then depresses listening key 8, whereupon her telephone head set is connected to the calling line. The calling subscriber may now converse with the operator and inform her of the number of the wanted line. 100

The cord circuit used by the operator 110

terminates at one end in an answering plug and in the other in an automatic switch. In order to simplify the disclosure, it has been assumed that the switch shaft has mounted upon it but one set of brushes and that this set of brushes serves a contact bank containing the terminals of 100 trunk lines arranged in 10 groups of 10 trunks each. The mechanical structure of the switch is a readily understood simplification of the 500 point switch, shown in Patent No. 1,123,696 issued Jan. 5, 1915, to E. B. Craft and J. N. Reynolds.

The operator, upon ascertaining the number of the wanted line, depresses keys in a key set (not shown) to control the sender shown within the dotted rectangle at the bottom of the drawing. In practice this sender would be associated with the desired 10 cord circuit by means of a cord finder. The cord finder and key set have been omitted since they are well known in the art. Patent No. 1,168,319 issued January 18, 1916, to A. E. Lundell shows complete circuits for 20 controlling a sender of the type which is diagrammatically indicated in the drawing of the present invention.

When the sequence switch (not shown), associated with the sending device, and 30 which controls sequence switch contacts 9 and 10, reaches position 2, a circuit is completed from grounded battery, winding of relay 11, lower right hand contact of sequence switch spring 12, conductor 13, armature and back contact of the O' counting relay, winding of stepping magnet 14, contact of sequence switch spring 9, conductor 15, lower contact of sequence switch spring 16, to ground. Relays 11 and 14 are energized in this circuit and relay 11, upon energizing, locks up through its left hand armature and front contact and the lower left hand contact of sequence switch spring 12 to grounded conductor 13.

45 Relay 11 at its right hand armature and front contact completes a circuit from grounded battery, power magnet of sequence switch 17, upper contact of sequence switch spring 18, right hand armature and front contact of relay 11 to ground, for moving this sequence switch out of position 1 and into position 2.

In position 2 of sequence switch 17 a 55 circuit is completed from grounded battery, winding of the up drive magnet 19, upper contact of sequence switch spring 20, right hand armature and front contact of relay 11 to ground. The energization of magnet 19 causes the brush shaft to be moved upwardly. As soon as commutator brush 21 engages the first conducting segment of 60 commutator 22 a circuit is completed from grounded battery, winding of relay 11, left hand armature and front contact of relay 11, lower left hand and upper right hand

70 contacts of sequence switch spring 12, conductor 23, commutator 22, commutator brush 21 to ground. Stepping magnet 14 is shunted down due to the fact that relay 11 has now found a direct path to ground. As 75 the brush shaft is moved upwardly, relay 14 is intermittently energized to control the operation of the counting relays in the well known manner. When the O' counting relay is energized, the circuit through stepping magnet 14 is permanently opened and when, a moment later, commutator brush 21 engages an insulating segment of commutator 22, relay 11 is de-energized and completes a circuit from grounded battery, 80 power magnet of sequence switch 17, the lower left hand contact of sequence switch 18, the right hand armature and back contact of relay 11 to ground, for moving this sequence switch out of position 2 and into 85 position 4. The de-energization of relay 11 also opens the circuit of the up drive magnet 19, thus causing the brush shaft to come to rest with the brush set engaging the contact set of the first trunk in the selected 90 group.

95 It will be assumed that the second group of trunks has been selected. If the first trunk in the group is busy this fact will be indicated by the presence of ground potential on the test terminal of such trunk. A circuit is thereupon completed from grounded battery, winding of relay 11, upper contact of sequence switch spring 27, test brush 25, test terminal 26, and thence to ground 100 by way of a sequence switch contact, corresponding to contact 27, associated with the switch which has seized such trunk. Relay 11 is energized in this circuit and completes a circuit from grounded battery, winding of updrive magnet 19, upper contact of sequence switch spring 20, right-hand armature and front contact of relay 11 to ground. The brush shaft is now again moved upwardly in a trunk hunting movement. As 110 soon as test brush 25 engages test terminal 28, which is associated with the first idle trunk in the group, relay 11 de-energizes, since no ground potential is found on such test terminal. The de-energization of relay 11 opens the circuit of up drive magnet 19, and causes the brush set to be brought to rest on the terminals of the idle trunk. The de-energization of relay 11 also completes a 115 circuit extending from grounded battery, power magnet of sequence switch 17, lower left hand contact of sequence switch spring 18, right hand armature and back contact of relay 11 to ground, for moving this sequence switch out of position 4 and into position 8.

120 As soon as sequence switch 17 reaches position 4, ground potential is supplied to test terminal 28 by way of test brush 25 and the lower contact of sequence switch spring 125 130

27 to render the trunk non-selectable to other hunting selector switches.

In position 8 of sequence switch 17, the auxiliary switch which controls the selection of a desired repeating coil ratio is brought into operation under the control of the interrupting device shown in the lower right hand portion of the drawing. This switch is a simple step-by-step switch which is advanced into a desired position under the control of a stepping magnet 65 and is restored to its normal position by continuing rotation until its normal position is reached. The mechanical structure of this switch is preferably similar to that shown in an application of O. F. Forsburg and R. M. De Vignier, Serial No. 317,126, filed August 13, 1919. The interrupting device comprises a plurality of impulse wheels mounted on a common shaft and continuously rotated by means of any desired form of prime mover.

As soon as the projection on pick-up interrupter wheel 67 engages the contact spring associated with this wheel, a circuit is completed from grounded battery, contact 68, conductor 69, upper inner armature and back contact of relay 24, winding of relay 24, lower armature and back contact of relay 29, terminal 40, brush 39, lower contact of sequence switch spring 42 to ground. Relay 24 is energized in this circuit and locks up over a circuit extending from grounded battery, inner upper armature, and its make-before-break contact, winding of relay 24 to ground over the path described.

Then energization of relay 24 connects impulse conductor 70 to terminal 30 by way of the outer upper armature and front contact of relay 24 and the upper armature and back contact of relay 29.

Stepping magnet 65 is now energized and de-energized three times under the control of impulse wheel 71, it being noted that wheel 71 is arranged to send three impulses. If a trunk in the first group had been selected, impulse conductor 72 would have been connected through to control stepping magnet 65 and only one impulse would have been sent. Only three off normal positions of the auxiliary switch have been indicated in the drawing, but it is obvious that any number of positions could be used and the impulse wheel may be arranged to send any desired number of impulses.

The first closure of impulse lead 70 to ground completes a circuit extending from grounded battery, winding of stepping magnet 65, winding of slow release relay 66, upper right hand contact of sequence switch spring 33, conductor 32, brush 31, terminal 30, upper armature and back contact of relay 29, outer upper armature and front contact of relay 24, conductor 70, contact 73 to ground. Stepping magnet 65

and relay 66 are energized in this circuit. As soon as the circuit of magnet 65 is opened, which occurs on the first opening of the contact 73, this magnet is de-energized and causes the auxiliary switch to advance 70 its wipers one step. Relay 66 being slow to release remains energized until the termination of the series of impulses.

The switch is caused to take 3 steps under the control of impulse wheel 71. After the third step, contact 73 remains open for a relatively long period of time and allows slow release relay 66 to de-energize. A circuit is then completed from grounded battery, power magnet of sequence switch 17, lower contact of sequence switch spring 74, an off-normal contact served by wiper 75, wiper 75, armature and back contact of relay 66 to ground, for moving this sequence switch out of position 8 and into position 10.

It is to be noted that when relay 24 was energized, it completed at its lower armature an energizing circuit for sleeve relay 36. Relay 36 upon energization locks up through its armature and front contact to ground by way of terminal 28, brush 25 and the lower contact of sequence switch spring 27.

As soon as sequence switch 17 leaves position 8, relay 24 is de-energized due to the opening of the lower contact of sequence switch spring 42. The de-energization of relay 24 completes a circuit extending from grounded battery, winding of relay 29, lower armature and back contact of relay 24, armature and front contact of relay 36 to ground as described. Relay 29 is energized and by attracting its armatures connects the tip and ring conductors through to the main tip and ring conductors 37 and 38 of the selected trunk.

When sequence switch 17 comes to rest in position 10, the fundamental circuit is extended to the succeeding switch in the train. The fundamental circuit may be traced from trunk conductor 37, upper armature and front contact of relay 29, terminal 30, brush 31, the lower contact of sequence switch spring 33, conductor 13, armature and back contact of the O' counting relay, winding of stepping magnet 14, sequence switch spring 9, conductor 15, upper contact of sequence switch spring 16, brush 39, terminal 40, lower armature and front contact of relay 29 to ring trunk conductor 38. Succeeding switches in the train are actuated in the well known manner under the control of the sender. The completion of each selective operation will cause the advance of the sender sequence switch and when the sender sequence switch reaches position 14, at which time it will be assumed that all selective operations of the switches have been completed, a circuit is completed from grounded battery,

120
125
130

power magnet of sequence switch 17, contact of sequence switch spring 41, contact of sequence switch 10 to ground, for moving sequence switch 17 out of position 5 10 and into position 16.

In position 16 of sequence switch 17, the talking connection is completed at the district switch by means of closures at sequence switch springs 33 and 42. Assuming that 10 the called subscriber has answered, supervisory relay 43 will have been energized. The circuit of the secondary winding of the district repeating coil may then be traced from grounded battery, lower right hand 15 winding of repeating coil 45, it being observed that a minimum number of turns are included, switch wiper 76 and its third off-normal contact, winding of supervisory relay 44, upper contact of sequence switch 20 spring 42, brush 39, terminal 40, lower armature and front contact of relay 29, trunk conductor 38, lower left hand winding of repeating coil 46, armature and front 25 contact of relay 43, resistance 47, upper left hand winding of repeating coil 46, trunk conductor 37, upper armature and front contact of relay 29, terminal 30, brush 31, conductor 32, upper left hand contact of 30 sequence switch spring 33, switch wiper 77 and its third off-normal contact and the upper right-hand winding of repeating coil 45 to ground.

It is to be observed that the selection of 35 a trunk in the second group, which is characterized by having an impulse lead connection such that three impulses will be supplied to the auxiliary switch, will result in the selection of the minimum ratio of the number of turns in the secondary winding 40 of repeating coil 45 to those in the primary winding.

The connection having been completed, the subscribers may now converse, it being noted that calling supervisory relay 48 was 45 energized when the operator first inserted plug 5 into jack 6.

When connection is no longer desired, both calling and called subscribers will replace their receivers on their switchhooks. 50 The replacal of the calling subscriber's receiver causes the de-energization of relay 48, and the replacal of the called subscriber's receiver results in the de-energization of relay 43. The de-energization of relay 43 causes in turn the de-energization of relay 44. The operation of the supervisory signals (not shown) controlled by relays 48 and 44 respectively, informs the operator that connection is no longer desired and she thereupon removes plug 5 from jack 6.

The removal of plug 5 from jack 6 interrupts the circuit of relay 7 and this relay de-energizes and completes a circuit from 60 grounded battery, power magnet of sequence switch 17, lower right hand contact of se-

quence switch spring 18, armature and back contact of relay 7 to ground, for moving this sequence switch out of position 16 and into position 18.

In position 18 of sequence switch 17, a circuit is completed from grounded battery, winding of stepping magnet 65, armature and back contact of magnet 65, upper contact of sequence switch spring 74, off-normal contact of wiper 75, wiper 75, armature and back contact of relay 66 to ground. Stepping magnet 65 is energized in this circuit and interrupts its own circuit to advance the switch wipers one step. Magnet 65 continues to interrupt its own circuit intermittently until the switch reaches its normal position at which time the circuit through wiper 75 will be opened.

When the auxiliary switch reaches its normal position, a circuit is completed from grounded battery, winding of down drive magnet 49, contact of sequence switch spring 50, wiper 75 and its normal contact, armature and back contact of relay 66 to ground. The brush shaft is returned to its normal position under the control of magnet 49 and as soon as commutator brush 21 engages normal commutator segment 51, a circuit is completed from grounded battery, winding of power magnet of sequence switch 17, lower contact of sequence switch spring 52, commutator segment 51, commutator brush 21 to ground, for moving sequence switch 17 out of position 18 and into position 1.

As soon as the brush set leaves the terminals of the trunk, the release of the succeeding switches in the train takes place in the well known manner.

It is obvious that only one interrupting device is necessary to supply impulses to all the outgoing lines in an exchange. The operation of the pick-up interrupter wheel will prevent any possible confusion in the distribution of the impulses. Connection to the various outgoing lines from the interrupter brushes may be made through any desired, well known form of cross connecting frame.

What is claimed is:

1. In a telephone exchange system, incoming lines, outgoing lines, a link circuit to be used in establishing connection between an incoming line and an outgoing line, a repeating coil associated with said link circuit, said repeating coil comprising a primary winding and a secondary winding, a switching device for varying the ratio of the number of turns of said secondary winding to the number of turns of said primary winding, and means associated with said outgoing lines to supply impulses to control the operation of said switching device.

2. In a telephone exchange system, incoming lines, outgoing lines, a link circuit to be used in establishing a connection be-

5   tween an incoming line and an outgoing line, a repeating coil associated with said link circuit, said repeating coil comprising a primary winding and a secondary winding, a switching device for varying the ratio of the number of turns of said secondary winding to the number of turns of said primary winding, an impulse producing device common to said outgoing lines, 10 and means for positioning said switching device under the control of said impulse producing device when connection is established from an incoming line to an outgoing line by means of said link circuit.

15   3. In a telephone exchange system, an automatic switch comprising a set of movable contacts and a plurality of sets of stationary contacts, a link circuit terminating in said movable contact set, a plurality of outgoing lines terminating in said stationary contact sets, means to supply series of impulses to said contact sets, said series of impulses varying in number in accordance with the character of said outgoing lines, a repeating coil associated with said link circuit, said repeating coil comprising a primary winding and a secondary winding, and a switching device variably responsive to said series of impulses to vary the ratio 20 of the number of turns of said secondary winding to the number of turns of said primary winding.

25   4. In a telephone exchange system, an automatic switch comprising a set of movable contacts and a plurality of stationary contact sets, a link circuit terminating in said movable contact set, a plurality of outgoing lines terminating in said stationary contact sets, a progression controlling device, an auxiliary switch associated with said automatic switch, means to operate said automatic switch in a hunting movement to select an outgoing line which is in a desired 30 condition, a repeating coil associated with

said link circuit, said repeating coil comprising a primary winding and a secondary winding, and means operative in a certain position of said progression controlling device to advance said auxiliary switch in accordance with characteristics of the selected 35 outgoing line.

5. In a telephone exchange system, an automatic switch comprising a set of movable contacts and a plurality of sets of stationary contacts, a link circuit terminating in said movable contact set, a plurality of outgoing lines terminating in said stationary contact sets, a progression switch and an auxiliary step-by-step switch associated with said automatic switch, means to operate said automatic switch in a hunting movement to select an outgoing line in a desired condition, a repeating coil associated with said link circuit, said repeating coil comprising a primary winding and a secondary 45 winding, and means to supply a variable number of impulses in accordance with the character of the outgoing line selected to operate said step-by-step auxiliary switch to vary the ratio of the number of turns of 50 said secondary winding to the number of turns of said primary winding.

6. In a telephone exchange system, incoming lines, means to transmit voice currents over said incoming lines, outgoing lines, a link circuit to be used in establishing connection between an incoming line and an outgoing line, a device associated with said link circuit, said device being arranged to modify voice currents received over said incoming line, a switch device for varying the degree of modification of said voice currents, and means associated with said outgoing lines to supply impulses to control the operation of said switching device. 65

In witness whereof, I hereunto subscribe my name this 23 day of Aug., A. D. 1920.

ALBEN E. LUNDELL.
